United States Patent Office.

NOAH MAYO AND EBEN S. MORSE, OF BATH, MAINE.

Letters Patent No. 94,016, dated August 24, 1869.

IMPROVED SHOW-CASE FOR COUNTERS.

The Schedule referred to in these Letters Patent and making part of the same.

To all whom it may concern:

Be it known that we, NOAH MAYO and EBEN S. MORSE, of Bath, in the county of Sagadahoc, and State of Maine, have invented certain new and useful Improvements in the Construction of Show-Cases for Counters, and the mode of opening and closing the doors or mirrors; and the following is a full, clear, and exact description of the same, reference being had to the accompanying drawings, making a part of this specification, in which—

Figure 1 represents a perspective view of a show-case, with one of the mirrors or sliding doors open.

Figure 2 shows a broken-off section of frame and slide, with friction-spring to hold it.

Figure 3 shows a friction-spring, detached.

The object of our invention is to make the most simple, cheap, and durable show cases, for all of the various trades and purposes for which they are used; and

Our invention consists in the application and arrangement of the sliding doors or shutters in which the mirrors are framed, and the friction-springs, or equivalent means for holding the sliding doors closed, are secured, so that the cases are more convenient, the mirrors more safe, and less room is required behind the counter, and things can be reached in wider cases than they can be when the doors are hinged to open outward.

To enable others to make and use our invention, we will describe it more in detail, referring to the drawings, and to the letters marked thereon.

We make our improved show-cases A in any desired form, or of any required dimensions.

The frame for holding the plate-glass is constructed in the ordinary manner.

The back frame B, to which the doors D D are fitted, is provided with grooves c c, in which the doors or shutters slide, there being spaces left in the rear of the bottom sill for that purpose.

In the grooves of the end and middle stiles a a we fit and secure steel springs b, or their equivalents, of sufficient capacity to hold the sliding shutters D D closed, or in any position, the sliding doors forming the frames for the reflecting-mirrors, which are not exposed, nor liable to be broken by opening or falling down, as those are which are hinged to be opened outward.

The sliding doors or shutters D have knobs d d, to open and close them by, which also serve the purpose

of stops, to prevent the doors from being slid out of the grooves c c, by the knobs coming in contact with a cleat or strip of wood, E, secured to the base of the frame on the outside.

When show-cases are required to be made of considerable depth, the doors being hinged at the bottom in the usual manner, they require a considerable space behind the counter, to admit of their being opened, and the mirrors are very liable to be broken, as they face outside, and are pressed upon by reaching in, and have to swing clear over and down, in order to get to the forward part of the case.

The advantages of our improved method of constructing show-cases, and the arrangement of sliding the doors, for getting into the case, and holding them in any position, either closed or open, will readily be seen and appreciated, and may be enumerated as follows:

The cases can be made cheaper, the sliding doors fitted more easily and closer, to keep out the dust; are more conveniently opened and closed; less liable to get out of repair or broken; dispense with hinges and catches, and economize room, which is a great desideratum in narrow stores and sales-rooms.

Our improved show-cases are set on a counter or stand, with the back edge of the case projecting over the edge of the counter sufficient for the doors to slide by, and when pressed down by the knob, do not come in contact, necessarily, with anything. They may be partially opened at the top, which will be often quite sufficient for the purpose, or when clear down, the mirror is protected by the back of the door, the same as when it is closed.

We do not claim, broadly, the use of sliding frames, sash, or doors, for opening or closing, nor friction-springs, for holding slides in position; for they are old and common property; but

What we do claim as our invention, and desire to secure by Letters Patent, is—

A counter show-case, constructed substantially in the manner as herein described.

In testimony whereof, we jointly hereunto subscribe our names, in the presence of—

NOAH MAYO.
EBEN S. MORSE.
